CLAIM

An ornamental design for a snap-on hair stylist's tray, as shown.

DESCRIPTION

FIG. 1 is a side elevational view of a snap-on hair stylist's tray showing my new design,

FIG. 2 is a top plan view,

FIG. 3 is a bottom plan view;

FIG. 4 is an end elevational view;

FIG. 5 is a perspective view showing a portion of the bracket which is folded over the end wall of the receptacle and overlies a portion of the inner surface thereof.

FIG. 1FIG. 2FIG. 3FIG. 4*FIG. 5*
